WASH FOUNTAIN

Howard G. Mullett and Edward D. Wachter, Jr.,
Whitefish Bay, Wis., assignors to Bradley Wash-
fountain Co., Milwaukee, Wis., a corporation of
Wisconsin

Application December 15, 1943, Serial No. 514,380

9 Claims. (Cl. 4—191)

The invention relates to group washfountains. The general object of the invention is to improve and simplify the fixtures of a group washfountain, so that they may be readily used to suit different installation conditions, that is, whether the water is supplied from above or below the basin and whether a vent pipe is used. More particularly, the invention is designed to provide a spray head fixture which may be supplied with water either from above or below and may have the water control and a vent pipe extend through a centrally disposed opening therein.

The invention further consists in the several features hereinafter set forth and more particularly defined by claims at the conclusion hereof.

In the drawings:

Fig. 1 is a vertical sectional view through a washfountain embodying the invention, taken on the line 1—1 of Fig. 2;

Fig. 2 is a plan view of the fountain, parts being broken away;

Fig. 3 is a detailed sectional view taken on the line 3—3 of Fig. 2;

Fig. 4 is an enlarged detailed sectional view taken on the line 4—4 of Fig. 2;

Fig. 5 is a detailed horizontal sectional view on the line 5—5 of Fig. 4;

Fig. 6 is a detailed view showing the fountain arranged for an overhead water supply;

Fig. 7 is a detailed sectional view through a washfountain embodying the invention taken on the line 7—7 of Fig. 8;

Fig. 8 is a plan view of a semi-circular washfountain having its water supply from below.

Referring to Figs. 1 to 5 wherein a washfountain having the water supply from below and a vent pipe is used in connection with the drain, the numeral 10 designates a pedestal which may be of any suitable material and which has the wash basin 11 mounted thereon which may be of circular or polygonal form and about which bathers may arrange themselves so as to secure the benefit from streams of water issuing from a centrally located spray head 12. The pedestal and basin are shown as made of cementitious material, but they may be of metal or other suitable material.

The spray head 12, as shown in Fig. 4, is of improved form being made of two parts 13 and 14 which form an annular shaped structure having a plurality of peripherally spaced spray passages 15 directing the water downwardly and toward the side of the basin. The passages 15

are formed by slots 16 milled in the top edge 17 of the part 14, the tops of said slots being covered by the plain faced edge 18 of the part 13, these edges with the slots being inclined as shown in Fig. 4. The part 13 provides the top wall 19 and an inner annular wall 20 in addition to a part of the outer wall. The part 14 forms the bottom wall 21 and the remaining part of the circular outer wall 22. The outer wall portions of the parts 13 and 14 may be held in abutting engagement with each other by any suitable clamping means and are here shown as clamped by a series of studs 23 mounted on the part 13 and passing through openings 24 in the part 14 and carrying clamping nuts 25 here shown as wing nuts. Machine screws or bolts whose heads bear against the part 14 and whose shanks have threaded engagement with the part 13 may also be used to hold the parts 13 and 14 together, if desired. The inner wall 20 of the part 13 is connected with the bottom wall 21 of the part 14 by the same clamping means, and this joint is preferably sealed by a compressible gasket 26. Making the parts of two pieces facilitates formation of the spray passages and also permits these passages to be cleaned by separating the part 14 from the part 13 without the necessity of disassembling other parts.

The inner wall 20 of the part 13 has a hollow boss 27 projecting inwardly therefrom and having top and bottom threaded pipe openings 28 and 29, one of which is normally closed by a pipe plug 30 and the other of which has the tempered water supply pipe 31 connected thereto. This inner wall also has annular recesses 32 formed on its top and bottom, the bottom recess adapted to receive the top edge of a hollow support 33, and the top recess adapted to receive a cap 34.

The top surface of the top wall 19 slopes downwardly from the center to a peripheral ridge 35 which is broken up at spaced intervals by drain passages 36, and this forms a soap tray for bar soap.

The spray head 12 is mounted above the basin 11, as previously noted, upon the tubular support 33 which seats at its lower end in a recess 37 surrounding the upper end of a centrally disposed opening 38 in the basin 11. The joint between the support 33 and the basin 11 is made water-tight by cement. The spray head 12 may be held against the top of the support 33 by any suitable tensioning means. As shown in Figs. 1 to 5, the vent pipe 40 forms a support extending up through the opening 38, the support 33, and the opening in the spray head and has an an-

nular cap or collar 41 mounted thereon which is adapted to fit the top recess 32 and be secured to the pipe 40 by a plurality of set screws 42 or other suitable fastening means.

The vent pipe 40 connects at its lower end with the intermediate portion of a trap 43, one end of which connects with a drain fitting 44 and the other end with the drain pipe 45. The fitting 44 is mounted in a fluid-tight manner in an opening 46 in the basin offset from the central opening 38.

The water pipe 31 extends from the spray head 12 down through the support 33 and the opening 38 to a position within the pedestal 10 where it connects with a volume control valve 47 whose stem has a control rod extension 48 that extends up through the opening 38, support 33, the interior of the spray head, and an opening 49 in the collar 41 and at its upper end carries a handle accessible to an operator at the side of the basin.

The valve 47 is supplied with tempered water by a mixture regulating valve (not shown in detail) whose stem 50 projects out through the pedestal and carries an operating handle 51, said valve controlling the proportional amount of hot and cold water flowing into the valve fixture through a hot water pipe 52 and a cold water pipe 53.

Where, as shown in Fig. 6, the water supply comes to the fountain from above through hot and cold water supply pipes 54 connected with a mixture control valve structure 55 having an operating handle 56 and supply tempered water to a pipe 57 controlled by a volume control valve having a handle 58, the pipe 57 is connected to the opening 28 of the spray head 12 and the opening 29 is closed by the plug 30 and the cap 41 has the opening 49 in it made big enough to receive the pipe 57.

Where no vent pipe is used and the water supply comes in from below, the arrangement is modified as shown in Figs. 7 and 8 in connection with a semi-circular wash-fountain having a pedestal 59 and basin 60 with a centrally disposed opening 61 and an offset drain 62 connected by a trap 63 with the drain pipe 64. The spray head 65 is identical with that previously described except that the lower member 22 has the spray slots 16 formed therein on a little more than one-half of its circumference.

The spray head 65 is supported above the basin 60 by a tubular or hollow support 66 which is identical to the support 33 and similarly fitted at its upper end in the recess 32 of the spray head and similarly mounted at its lower end in the recess 67 at the upper end of the opening 61.

The spray head 65 is secured to the top of the support 66 by tensioning means comprising a tension rod 68 threaded at both ends, the lower end secured by a nut 69 to a cross bar 70 extending across the basin below the opening 61 and the upper end secured by a nut 71 to a cover plate 72, similar to the cover 41 except for the lack of the opening for the vent pipe. The tempered water supply pipe 31 is similar to that of the first described construction and similarly controlled from above, so that similar reference numerals have been applied to these parts.

Where, with the water supply from above, the vent pipe is not used, then a cover plate similar to the plate 72 with an opening to admit the supply pipe is used in place of the plate 41 shown in Fig. 6.

We desire it to be understood that this inven-

tion is not to be limited to any specific form or arrangement of parts except in so far as such limitations are included in the claims.

What we claim as our invention is:

- 5 1. In a washfountain having a wash basin with an opening therein and a hollow support mounted centrally of a peripheral portion of said basin and in line with the opening in said basin, the combination of a spray head mounted on the top of said support, and means, distinct from said support, to clamp said spray head against the top of said support.
- 10 2. In a washfountain having a wash basin with an opening therein and a hollow support mounted centrally of a peripheral portion of said basin and in line with the opening in said basin, the combination of an annular spray head mounted on the top of said support, means, distinct from said support, to clamp said spray head against the top of said support including a member mounted on the top of said spray head and projecting over the opening therein.
- 15 3. In a washfountain having a wash basin with an opening therein and a hollow support mounted centrally of a peripheral portion of said basin and in line with the opening in said basin, the combination of an annular spray head mounted on the top of said support and having an inwardly projecting hollow boss provided with
- 20 30 alined top and bottom outlets, means for closing one of said outlets, and a water supply pipe connected to the other of said outlets.
- 25 4. In a washfountain having a wash basin with an opening therein and a hollow support mounted centrally of a peripheral portion of said basin and in line with said opening, the combination of an annular spray head mounted on the top of said support and having a top surface dished downwardly from its central portion to its outer edge, said outer edge formed by a plurality of spaced retainer portions and cooperating with said surface to form a soap tray, and means for holding said spray head against said support.
- 35 45 5. In a washfountain having a wash basin with an opening therein and a drain passage offset from said opening, a hollow support mounted centrally of the peripheral portion of said basin and in line with the first named opening, a vent pipe extending through said opening, a trap connected to said drain opening and said vent pipe, an annular spray head mounted on said support and through which said vent pipe projects, and a collar secured to said vent pipe and spacing said vent pipe from said spray head and holding said spray head against the top of said support, and means for supplying water to said spray head.
- 50 55 6. In a washfountain having a wash basin with an opening therein and a hollow support mounted centrally of a peripheral portion of said basin and in line with said opening, the combination of an annular spray head mounted on the top of said support, means, distinct from said support, to clamp said spray head against the top of said support including the cover member mounted on the top of said spray head and projecting over the opening therein, a water supply pipe extending from below the basin through said opening and support to said spray head, a volume control valve connected to said pipe below the basin, an operating means for said valve comprising a rod extending through said opening, said hollow support, and an opening in said cover member, and a handle mounted on said operating rod above said spray head.
- 60 65 70 75 7. In a washfountain having a wash basin with

an opening therein and a hollow support mounted centrally of a peripheral portion of said basin and in line with the opening in said basin, the combination of an annular spray head mounted on the top of said support, and tensioning means including a tie rod and a cap member engaging the top of said spray head to hold it in position on said support, and means for supplying water to said spray head.

8. In a washfountain having a wash basin with an opening therein and a drain passage offset from said opening, a hollow support mounted centrally of the peripheral portion of said basin and in line with the first named opening, a vent pipe extending through said opening, a trap connected to said drain opening and said vent pipe, an annular spray head mounted on said support and through which said vent pipe projects, a collar secured to said vent pipe and spacing said vent pipe from said spray head and clamping said spray head against the top of said support, a water supply pipe extending from below the basin through said opening and support to said spray head and connected to the inner wall thereof, a volume control valve connected to said pipe below the basin, operating means for said valve including a rod extending through said opening, said hollow support, and an opening in said collar, and a handle mounted on said operating rod above said spray head.

9. In a washfountain having a basin with an opening therein and a hollow support mounted centrally of a peripheral portion of said basin and in line with said opening, the combination of a two-part annular spray head, one of said parts forming a part of the outer wall, the top wall, and the inner wall of said spray head, the bottom portion of the inner wall being mounted on said support, the other of said parts forming the remainder of the outer wall and the bottom wall of said spray head, means for clamping said parts of the spray head together, the joint between the outer wall portions of said parts being formed on an incline and one of said parts provided with slots to form spray passages, a compressible gasket for the joint between the inner wall of the first named part of said spray head and the bottom wall of the second named part, said second named part of the spray head on release adapted to be moved relative to the first part and said support, said first named part of the spray head having a water supply connection in its inner wall, a water supply pipe connected with said connection, and control means adjacent said spray head for said supply pipe.

HOWARD G. MULLETT.
